OIL FILLER BREATHER CAP

Frederick M. Hill, Columbus, and Bernard Stockwell, Sunbury, Ohio, assignors to Stant Manufacturing Company, Inc., Connersville, Ind., a corporation of Indiana

Filed Mar. 8, 1962, Ser. No. 69,155

Term of patent 14 years

(Cl. D14—6)

Fig. 1.

Fig. 2.

Fig. 3.

Fig. 4.

Fig. 5.

FIG. 1 is a perspective view of an oil filler breather cap embodying our new design;

FIG. 2 is an enlarged, side elevational view taken approximately 135° from FIG. 1;

FIG. 3 is a top plan view thereof; and

FIG. 4 is a bottom plan view thereof.

FIG. 5 is a perspective view taken approximately 180° from FIG. 1.

The dominant features of our design reside in the portions shown in full lines.

We claim:

The ornamental design for an oil filler breather cap, as shown and described.
